Patented Mar. 31, 1970

217,060

ANIMAL FEEDER

Lawrence A. Wilson, 10068 Sakura Drive,
St. Louis, Mo. 63128

Filed Dec. 23, 1968, Ser. No. 15,087

Term of patent 14 years

Int. Cl. D30—02

U.S. Cl. D30—16

FIG. 1

FIG. 2

FIG. 3

FIG. 4

FIG. 5

FIGURE 1 is a perspective view of an animal feeder showing my new design.

FIGURE 2 is a back view.

FIGURE 3 is a front view.

FIGURE 4 is a top view.

FIGURE 5 is a vertical transverse sectional view taken on the line 5—5 of FIGURE 1.

The feed bowl shown in broken lines in FIGURE 5 is depicted for illustrative purposes only.

I claim:

The ornamental design for an animal feeder, substantially as shown and described.
